UNITED STATES PATENT OFFICE.

H. E. FOWLER, OF NEW HAVEN, CONNECTICUT, ASSIGNOR OF ONE-HALF TO LEVI N. BLYDENBURG, OF SAME PLACE.

BRUSH.

SPECIFICATION forming part of Letters Patent No. 359,250, dated March 15, 1887.
Application filed July 19, 1886. Serial No. 208,376. (No model.)

To all whom it may concern:

Be it known that I, HERBERT E. FOWLER, of New Haven, in the county of New Haven and State of Connecticut, have invented a new 5 Improvement in Brushes, and I do hereby declare the following, when taken in connection with accompanying drawings and the letters of reference marked thereon, to be a full, clear, and exact description of the same, and which 10 said drawings constitute part of this specification, and represent, in—

Figure 1, a perspective view, looking upon the face of the brush; Fig. 2, a transverse section of the same; Fig. 3, a longitudinal section of the same through one of the grooves; Fig. 15 4, a perspective view of the wire and fibers interwoven preparatory to introduction to the block. Figs. 5 and 6 illustrate methods of 20 interweaving the fibers and wire; Fig. 7, a modification of the grooves in the block.

This invention relates to an improvement in that class of brushes in which the bristles are usually set in blocks—such as tooth-brushes, hair-brushes, blacking-brushes, scrubbing-brushes, and the like. In the more general 25 construction of this class of brushes the block is drilled with a separate hole for each tuft and each tuft requires independent fastening.

The object of my invention is to reduce the 30 cost of setting and make the brush equally if not more durable than the common tuft brushes; and the invention consists in interweaving the fibers with a continuous twist of wire, then setting the wire in the requisite 35 lengths in the grooves in the brush-block, as more fully hereinafter described.

In preparing the bristles or fibers for application to the back, I twist together two strands of wire, *a a*, Fig. 4, and in the process of twisting interweave the fibers by doubling the fiber around one or both wires, as seen in Fig. 5, or placing them between the wires, as seen in Fig. 6. Then in twisting the wires the fiber is doubled sufficiently to permit the wire to pass into the groove of the block, and the sides of the groove in the block bring the fibers into their proper relative position, making the succession of fibers substantially continuous. The wire thus filled 50 with fiber is ready for the block.

The block A is constructed with grooves *b*, preferably undercut, and of a diameter somewhat greater than the diameter of the twisted wire and fiber, but in width so that the wire may be drawn through the grooves. The wire 55 is cut in the requisite lengths and drawn into the grooves, as represented in Fig. 2. The overhanging part of the groove may be sufficient to hold the wire and fibers firmly. The fibers extend from the groove and naturally 60 spread, so as to present a solid fiber surface, as shown. The groove may be, as seen in Fig. 7, of equal width, and the wire introduced with glue or similar cement to embed the wire and secure it in place. The groove 65 may be longitudinal, as represented in Fig. 1, or of any desirable shape, according to the style or character of the brush. By this construction the fibers are very rapidly prepared in long continuous runs of wire ready to be 70 cut. These may be produced by hand; but I propose to combine the wire and fiber by a machine which will constitute the subject of an independent application for patent. After the fibers have been set the face of the brush 75 is trimmed in the usual manner.

In this construction of brush there is no liability of the fibers becoming detached, as in many brushes in which the fibers are set in tufts, and the brush is cheaply produced and 80 of the most durable character.

While I prefer to make the strands with which the fibers are interwoven from wire, for the reason that it is cheap and strong, it will be understood that other material may be 85 used for the strands—such, for illustration, as a strong twine.

I claim—

The herein-described improvement in brushes, consisting in twisted strands having fibers 90 interwoven therewith, and so as to project therefrom, and a block constructed with one or more grooves, into which the said twisted strands holding the fibers are set, substantially as described.

HERBERT E. FOWLER.
